UNITED STATES PATENT OFFICE.

JILES S. SHOCKLEY, OF NASHVILLE, TENNESSEE.

ROTARY PUMP.

1,371,121.

Specification of Letters Patent. Patented Mar. 8, 1921.

Application filed January 21, 1920. Serial No. 352,958.

To all whom it may concern:

Be it known that I, JILES S. SHOCKLEY, a citizen of the United States, residing at Nashville, in the county of Davidson and State of Tennessee, have invented certain new and useful Improvements in Rotary Pumps, of which the following is a specification.

This invention relates to rotary pumps, and more particularly to the duplex type having two pistons mounted near opposite ends of and receiving power from a single shaft.

One object of the present invention is to reduce to a minimum the number of parts, fittings and couplings of a pump of this character whereby such a pump may be economically constructed and a compact simple structure produced.

Another object of the present invention is to provide a pump in which there is a minimum loss of power, with the greatest piston action, thereby increasing the final efficiency of the machine.

A still further object is to provide an efficiently operating valve mechanism separating the inlet and discharge currents of water in the piston chamber.

Still further objects will appear from the description and claims following, and reside in the particular combination of parts and mode of operation herein described.

One embodiment of the present invention is illustrated in the accompanying drawings, in which—

Figure 1, is a front elevation of the complete pump. Fig. 2, is a top plan view thereof. Fig. 3, is a side elevation of said pump. Fig. 4, is a detail cross section of one of the piston chambers illustrating the abutment valve arrangement in detail. Fig. 5, is a detail perspective of the abutment valve.

Like reference characters refer to like parts throughout the drawings, wherein numeral 1 designates the rectangular shaped base of the herein described pump. This base may be secured to any proper stand or to the floor wherever desired. At each end of the rectangle the base 1 has an upright extension 2 upon the top of which are the piston chambers 3 and 4 appropriately secured to the base by any convenient or proper method, such as by bolts, as shown in the drawings. The piston chambers 3 and 4 are closed at their ends by the heads

3' and 4', also shown as bolted to the piston chamber covers.

Extending transversely between the piston chambers 3 and 4 is a crank shaft 5 having crank arms 13 (Fig. 3) in each of the piston chambers, upon which the piston rotors 12 are mounted. The crank arms 13 are oppositely disposed upon the crank shaft, accordingly, the pistons are oppositely disposed so that in their rotation, one is discharging while the other is charging, thereby keeping a continual flow of water from the pump. The hub of each piston rotor 12 is provided with a roller bearing 25 through which the crank arm passes, in the customary manner. Midway between the two piston chambers the shaft 5 has fast thereon a single pulley 6, which is a driven pulley, receiving power from any convenient source by means of the belt 6'. As the means for driving is not a part of the present invention, no illustration or description thereof is given. At each of the bearing points where the shaft 5 passes through the respective piston heads, there is provided a roller bearing within each of the packing boxes 8. (Figs. 1 and 2). The inner boxes 8 are made watertight by means of the packing nuts 7; and the outer boxes 8 are 85 so closed by the caps 8', as shown in Fig. 3.

The base 1 of the pump is cast hollow, with a transverse partition 23 therein which extends from one side of the base to the other and extends upwardly in the side extensions 2 terminating at the piston chambers, thereby dividing this hollow base into two passages or channels, designated by the reference characters 10 and 10' for the transverse channels in the base (Fig. 1) and 95 24, 24' for the channels in the side extensions leading to the piston chambers (shown best in Fig. 4). It will be noted from Fig. 1 of the drawings that passages 24, 24' merge with the horizontal channels 10, 10', 100 so as to form continuous channels on opposite sides of the partition 23.

Attention will now be called to the fact that by casting the base of the pump as above described so that the water circulates therethrough to and from the piston chambers, provides a most economical structure because of the saving of expensive well made couplings, fittings, pipe, etc., necessary on other types of pumps, and expensive 105 milling upon the interior of the cast base to form these channels. In addition, the

pump is reduced to simple compactness. Also, the working parts and parts requiring replacement are reduced to a minimum by this construction.

- 5 The base 1 has intermediate between its ends an opening 101 on each side of the pump, which respectively connect with the channels 10, 10' one of these openings being an inlet and the other an outlet for the 10 water. Surrounding each of the openings 101 is a flange 9, bolted to which are the collars of pipes 11 and 11' respectively. These pipes 11 and 11' lead from a source 15 of water supply, on one side, and away from the pump on the other side, respectively.

Water is supplied to the herein described pump through inlet pipe 11, opening 101, and passes through transverse horizontal passage 10 on either side of said opening, 20 into the channel 24, leading to the piston which is drawing water in. From here the water is partly forced and partly sucked through the inlet passage into the piston chamber, is taken up by the piston upon the 25 rotor 12, is discharged through the outlet passage 24' on the opposite side of the piston chamber, through the connecting transverse horizontal outlet passage 10', and out from the opposite side of the pump through 30 opening 101 and the outlet pipe 11'. While one piston is performing the first half of this cycle, the other piston is performing the other half, so that the action of the pistons is alternate and while one piston is 35 discharging, the other piston is drawing water in.

The piston being mounted upon the eccentric crank arms 13 of the shaft 5 described eccentric paths within the piston castings. 40 contacting with the inner surfaces thereof, as will be noted from Figs. 3 and 4 of the drawings, the partition 23 does not extend within the chambers so as to touch the piston rotor 12 in any of its positions. Because 45 of the eccentric path of the piston there is a varying distance between the top of the partition 23 and the piston 12 through which the incoming water from the passage 24 might escape or leak into the outgoing channel 24' without being taken up by the piston, and vice versa for the water being discharged from the piston. Accordingly, to 50 prevent such a situation and the consequent loss of efficiency in the pump, the present 55 invention contemplates an abutment valve indicated at 14. This valve is located in the channel 24 and extends above the top thereof extending the partition 23 to contact with the piston. As shown in detail 60 in Fig. 5, this valve 14, comprises longitudinally extending arms 15, which are pivoted at 19 to the piston casing. These arms are joined together at their free ends, this whole construction constituting a stem for the 65 valve. The stem 15 projects around the

channel 24 into a pocket 18 cast integral with the piston chamber cover. In the recess of the pocket 18 is located a spring 16, with which the end of the stem 15 contacts in such a way as to keep the spring 16 slightly 70 compressed. The opposite end of the spring 16 is secured to the protruding end of the bolt 17 which holds the cap of the pocket 18 in position. At the opposite end of the stem 15 there is provided a broad valve head 20 75 which is equal in width to the width of the inlet channel 24. The head 20 is slightly deeper than the greatest distance between the upper edge of the partition 23 and the piston when farthest removed from the 80 upper edge of the partition and inclines downwardly into the passage 24. The valve head 20 is movably held by the action of the spring 16 on the stem 15, in juxtaposition to the upper end of the partition 23 85 so as to become an extenuation thereof and at all times is held against the piston rotor 12. Thus, the varying opening between the top of the partition 23 and the piston rotor 12 is closed, thereby effectually keeping the 90 currents of water from intermingling with the consequent loss of efficiency. The valve head is able to respond to the eccentric swing of the piston by means of its pivoted stem and the action of the normally slightly compressed spring 16 which is further compressed as the piston swings downwardly and reaches its lowermost point, and the head automatically returns as the piston 95 recedes, keeping in constant contact therewith.

Between the movable valve head 20 and the partition 23 there remains a slight opening, which varies as the head rises and lowers, through which the water may leak. To 105 prevent such leakage, a packing strip 21 is inserted in a slot on the inlet side of the partition 23 from which it projects at an angle against the side of the valve head 20. Both the slot and the strip 21 correspond 110 in width to the width of the valve head and the inlet passage 24. In order that the strip 21 may yield as the inclined valve head descends, a series of coiled springs 22 are placed in the slot behind the strip 21. Normally, that is to say when the piston is at 115 its point farthest away from the partition 23, the springs 22 are slightly compressed so that the strip is kept in positive but yielding engagement with the head 20. As 120 the piston in its eccentric rotation descends forcing the valve head 20 downwardly, the strip 21 is forced further into the recess thereby further compressing the springs 22. Then, as the piston recedes, the springs 22 125 force the strip outwardly keeping it constantly in contact with the head 20 concurrently as the valve head 20 is kept in contact with the piston rotor 12. Hence there can be no intermingling of the two currents 130

of water in the piston chambers, nor can there be any leakage between the two channels for these channels are maintained distinct throughout the entire course of travel 5 of the water. Of course, what holds true of the incoming current of water being unable to get into the outgoing channel without being acted upon by the piston because of the abutment valve 14, also holds true of 10 the discharged water from the piston because of the intermediate position of the valve 14.

The abutment valve 14 and the coöperating mechanism, and the packing strip 21 15 have all been described for one piston chamber only. This has been done for convenience in understanding. There is a similar valve and coöperating mechanism, and a similar packing strip coöperating with the 20 valve head in each of the piston chambers.

I claim:

1. A rotary pump of the character described, comprising a base formed hollow with a transverse partition extending from 25 one side to the other, said base having upright extensions at the ends into which said partition extends, there being channels and 30 passages formed in continuity with each other on opposite sides of said partition, piston chambers on said extensions, a crank shaft extending transversely between said 35 piston chambers and having crank arms in said chambers, piston rotors mounted on said crank shafts and oppositely disposed and a pulley on said shaft between said chambers.

2. A rotary pump of the character described, comprising a base formed hollow with a transverse partition extending from 40 one side to the other, said base having upright extensions at the ends into which said partition extends, there being channels and 45 passages formed in continuity with each other on opposite sides of said partition, piston 50 chambers on said extensions, a crank shaft extending transversely between said piston chambers and having crank arms in said chambers, piston rotors mounted on said crank shafts and oppositely disposed, a pulley on said shaft between said chambers, and an abutment valve having a stem projecting into a pocket formed in the piston chamber cover.

3. A rotary pump of the character described, comprising a base formed hollow with a transverse partition extending from 55 the one side to the other, said base having upright extensions at the ends into which said partition extends, there being channels 60 and passages formed in continuity with each

other on opposite sides of said partition, piston chambers on said extensions, a crank shaft extending transversely between said piston chambers and having crank arms in 65 said chambers, piston rotors mounted on said crank shafts and oppositely disposed, a pulley on said shaft between said chambers, and means for varying the opening between the top of said partition and the piston rotors.

4. A rotary pump of the character de- 70 scribed, comprising a base formed hollow with a transverse partition extending from one side to the other, said base having upright extensions at the ends into which said partition extends, there being channels and 75 passages formed in continuity with each other on opposite sides of said partition, piston chambers on said extensions, a crank shaft extending transversely between said 80 piston chambers and having crank arms in said chambers, piston rotors mounted on said crank shafts and oppositely disposed, a pulley on said shaft between said chambers, the piston rotors being mounted for eccentric 85 rotation, a valve head adapted to be forced downwardly by such piston rotors, and a spring-actuated strip coöperatively arranged, as and for the purpose specified.

5. In a rotary pump of the character described including a base having openings at 90 its center and lateral channels from each side of said openings, piston casings at the outer ends of the channels, an eccentrically mounted piston in each casing, a shaft and crank arm carrying each piston, and an abut- 95 ment valve in the casing and operating on the piston, said valve being pivotally mounted in the piston casing, and a spring arranged to act upon the stem of said valve whereby the spring is normally slightly com- 100 pressed.

6. In a rotary pump of the character described, including a base having an inlet and an outlet opening at substantially a middle point and at different sides thereof and lateral channels terminating at said openings, 105 piston casings at the outer ends of the base and the channels, a shaft, a piston in each casing and at the ends of the shaft, crank arms on the shaft and carrying the pistons 110 eccentrically, and abutment valves yieldingly mounted to play against the edges of the pistons pivotally mounted in the piston casing, a spring bearing upon the stem of said bolt, said valve being in the form of a broad 115 head equal in width to the inlet channel to the piston chamber.

In testimony whereof I affix my signature.

JILES S. SHOCKLEY.
